MARBLE GAMEBOARD TOY

George Miller, Vancouver, British Columbia, Canada

Application March 30, 1959, Serial No. 55,259

Term of patent 3½ years

(Cl. D34—5)

I claim:

The ornamental design for a marble toy gameboard, as shown.
